UNITED STATES PATENT OFFICE

RUSSELL A. FRISBIE, OF MIDDLETOWN, CONNECTICUT, ASSIGNOR TO THE J. & E. STEVENS COMPANY, OF CROMWELL, CONNECTICUT, A CORPORATION

MACHINE GUN TOY PISTOL

Application filed August 15, 1930. Serial No. 475,489.

My invention relates to improvements in machine gun toy pistols of the form that is adapted to fire paper caps in strip form by the operation of a crank, and the object of my improvement is to produce a machine gun toy pistol that comprises a complete and fully operative trigger firing toy tape pistol, such for instance as the pistol structures shown and described in applications filed by myself 5 that issued as Patent No. 1,674,429, June 19, 1928, and No. 1,691,237, November 13, 1928, and in which is provided additional mechanism for use in firing by the crank.

In the accompanying drawing:—

Figure 1 is a side elevation of my improved machine gun toy pistol, the barrel portion being directed towards the left showing exposed in an opening in the casing adjacent the end of said barrel portion one end of the bearing barrel of the star-cam member that is rotated to effect the firing by the crank, the loading chamber cover being swung to one side.

Fig. 2 is a fragmentary view of the other 25 side of the barrel end portion, the crank being shown by broken lines.

Fig. 3 is a view on an enlarged scale showing the right casing member and the operating mechanism in position therein.

Fig. 4 is a similar view showing the star-cam member, the slide that is operated thereby, and the trigger member in a different position.

Fig. 5 is a sectional view through the star-cam member with the key-portion of the crank in engagement therewith.

Fig. 6 shows the driving end portion of the crank and the lug structure thereon.

Fig. 7 shows the key-entrance portion of 40 the casing and of the bearing barrel of the star-cam member.

In operating my improved machine gun toy pistol for rotary or machine gun firing a crank 10 is inserted in an opening 11 adjacent the outer end of the barrel portion 12 of the pistol structure so as to make drive connection with a star-cam member 13 for rotating the latter and intervening means effect the firing by operating the trigger member 24, the portion 15 of the latter that

is adapted to be engaged by the finger for finger firing and thus serves as the trigger proper being exposed and visible as usual within the space 16 that is enclosed by the guard 17.

In the form that is shown the finger operated firing mechanism corresponds to that of the patents mentioned and the difference in outside appearance is confined to the opening 11 mentioned and the end portions of the barrel bearing 18 of the star-cam member 13 60 that are exposed therein at the two ends of said opening 11.

At the left end of said bearing barrel 18 is a plain short cylindrical bearing 19 that merges with a shoulder 20 at the junction with the body 21. At the right end 22 is what is operatively a similar bearing, but which is provided with a key-slot 23 for driving engagement with a radial drive lug 24 on the body 25 of the crank 10. The wall structures 26 of the casing 27 are suitably spaced apart and of proper thickness so as to operatively hold and guide the bearing barrel 18 under operative conditions.

The key slot 23 extends inwardly along the bearing barrel 18 beyond and across the end bearing 22 and across the adjacent portion of the body 21 and beyond the supporting wall 26; the lug 24 also extends inwardly along the crank body 25 to correspond; and the inner end portion of said lug 24 is provided with an extension 27 that projects radially outwardly beyond the adjacent portion of the lug 24. Said extension 27 serves as a retaining lug to prevent removal of the crank 10.

The opening 11 in the wall structure 26 at the right crank-receiving side besides the circular form for providing the supporting bearing for bearing barrel end 22 is provided with a radial slot 28 for admitting the extension to the open space 29 at the inner side of the side wall 26. Thus the extension 27 is adapted to rotate in said space 29 when the crank body 25 is rotated and at the same time will engage with the opposed inner face of the side wall portion 26 to prevent outward movement and thus prevent removal of the crank. That is to say, such removal 100

of the crank 10 is prevented at all positions of the crank as it is rotated except when the extension or holding lug 27 is in registration with the admission slot 28 in the casing wall 5. 26. Under conditions of use, as the crank is rotated, the holding lug 27 is continually carried by momentum past the admission slot 28 so that it operates virtually as a positive means for preventing accidental removal of 10 the crank.

At the middle of the bearing barrel 18 is the star-cam structure which comprises, as shown, a set of three saw-tooth teeth 30 spaced around the body 21.

15. The teeth 30 drive the trigger member 14 through the medium of a slide 31 that has on one edge a drive lug 32 for cooperating therewith and that is projected rearwardly so as to abut against the trigger member 14 by its end face 33 at an edge portion 34 thereof just above the finger grip or trigger proper 15. Thus means are provided for operating the trigger member by the use of a crank instead of the finger.

20. 25. The slide 31 operates longitudinally to and fro in a suitable way 35 that is provided in the casing and operates as a ram. The propelling lug 32 is at the upper edge of the slide 31 and this operates between limits provided by a pair of lugs 36 that also constitute parts of the way 35.

Forward movement of the slide 31 may be limited by means of a dependent lug or extension 37 at the rear end portion of the 35 bottom edge that is opposed to the adjacent portion 38 of the guard 17.

The details as to the trigger member and the mechanism operated thereby may be of varied form. One form to which the same 40 is adapted is that of the devices shown and described in the patents mentioned, and this form will now be briefly described for illustrative purposes.

45. Thus the trigger member 14 is pivoted by its upper end 39; is normally swung forwardly by its spring 40; such forward movement being limited by a stop means; and is provided with a rearwardly directed arm 42 that effects the firing by making operating engagement with a forwardly projecting arm 43 on the hammer member 44. In the pistols 50 of the patents mentioned a stop is provided on the casing for serving as the stop means mentioned. In the present structure the dependent lug 37 on the slide 31 serves this function.

55. The hammer propelling arm 43 forms a V-shaped structure with the adjacent portion of the hammer body 45 that provides by its apex 46 a bearing for the hammer member 44 in engagement with a post 47. The hammer is positioned and generally operatively supported by means of the hammer 60 spring 48. The striking face 49 is at the up-

per end and moves forwardly to meet the anvil 50.

The cap tape 51 has the roll portion mounted on a post 52 and the free end portion is threaded along what is virtually a slot 53 in the left side of the hammer member 44, 70 extending generally vertically from end to end of the hammer body 45. The forward wall 54 of the slot 53 is substantially continuous and provides a face for the tape end 75 to slide along.

A tape check spring member 55 serves by its free end portion as the means for preventing retrograde movement of the cap tape along the tape supporting wall 54; is supported so as to tend to press by its end against the tape when in position along said wall 54; is carried bodily by the hammer body 45; and is supported by its lower end portion in any proper manner as by the provision of a special shape for the said supporting end portion 56. A set of lugs 57 serves to cooperate with said shaped end portion 56 to provide a positive holding effect for the spring 55.

80. In cooperation with the check spring or pawl 55 for effecting the feed of the tape there is provided a feed pawl 58 that is pivotally supported and positioned for feeding by the feed pawl spring 59.

85. The hammer member normally makes contact with the anvil; is swung away therefrom by the trigger member when operated, whether by hand or finger or by the crank; the feeding of the tape is effected during the 90 swinging movement of the hammer member away from the anvil; a part of the tape is brought into registration with the anvil; and the firing is effected by the force of the hammer spring after the coacting parts of the 95 trigger member and the hammer member have slipped by one another. Release of the trigger members permits the trigger spring to restore the trigger member to the normal position. The trigger member carries with it during its return movement the slide after 100 crank operation.

105. The principles of the crank operation described are applicable to other forms of mechanism than such as has been described. In 110 particular such is the case with structures that provide for self-cocking or automatic return of the trigger member to the initial 115 position.

I claim as my invention:—

120. 1. In a machine gun toy pistol, a pistol structure comprising a casing and mechanism housed therein that is operative to fire paper caps in strip form repeatedly by successive pulling of the trigger, a star-cam 125 housed for rotative movement in said casing, and an intermediate member housed in said casing for reciprocating movement serving to operatively connect said star-cam and some part of said mechanism so as to effect 130

such firing responsive to rotation of said star-cam in substantially the same manner as by such pulling of the trigger.

2. In a machine gun toy pistol as described in claim 1, said trigger being part of a trigger member that is mounted in the casing for to and fro movement, said star-cam being provided with a set of saw-teeth on the periphery, and said intermediate member having a lug for driving that is brought into actuating contact with said saw-teeth during such rotation of said star-cam.
